United States Patent Office.

AUGUSTUS B. FELGEMAKER AND SILAS L. DERRICK, OF BUFFALO, NEW YORK.

Letters Patent No. 77,703, dated May 5, 1868.

PORTABLE PIPE-ORGAN.

The Schedule referred to in these Letters Patent and making part of the same.

TO ALL WHOM IT MAY CONCERN:

Be it known that we, AUGUSTUS B. FELGEMAKER and SILAS L. DERRICK, of the city of Buffalo, county of Erie, and State of New York, have invented a new and improved Portable Parlor Pipe-Organ; and we do hereby declare that the following is a full, clear, and exact description thereof, reference being had to the accompanying drawings, making a part of this specification, in which—

Figure I is a front elevation,
Figure II a transverse section,
Figure III a sectional top plan, and
Figure IV detail views of the vertical pipes, showing the manner of fastening them.
Figure V is an end view of our improved wind-chest, in connection with its valve-chamber.
Figure VI is a plan view and sections of the valve-board.
Figure VII is a plan and sections of the bottom of the wind-chest.
Figure VIII is a plan and sections of the air-passages in the first division.
Figure IX is a plan and sections of a partition between the first and second divisions.
Figure X is a plan and sections of the air-passages in the second division.
Figure XI is a plan and sections of the top board of the wind-chest, showing the position of three sets or rows of pipes in connection therewith.

The nature of this invention relates—

First, and broadly, to the construction of a portable parlor pipe-organ, that is to say, a parlor pipe-organ so constructed that all its parts may be put together in the manufactory, in proper condition for parlor use, and the organ packed and transported to its destination without displacing any of its parts, and then be in a fit condition for parlor use without retuning, and without the aid of a skillful workman to put it in order.

Secondly, and specifically, in the construction of a compound wind-chest, that is to say, a wind-chest made with two or more divisions, each division having distinct air-passages to supply a distinct set, or row, or rows, of pipes, whereby an instrument of great power and clearness of tone is made to occupy a smaller space than heretofore.

Letters of like name and kind refer to like parts in each of the figures.

A represents the casing of the instrument, which is rectangular, and has a slight projection at its front for the location of the key-board.

B B represent the keys of the instrument, the back ends of which are hinged upon a light framework, b^1 .

C represents the valve-chamber, which is located below the key-board, and as near to the floor as the construction and size of the bellows and foot-pedals will allow. The valves, c' , are hinged to the upper side within the valve-chamber, and operated by the long wooden pins or "stickers" b^2 , which pass through the key-board frame b^1 and the upper floor of the valve-chest, their top being in contact with the under side of the keys, and their foot end resting upon the top of the valves.

The construction of these parts is similar to the valve-action and key-board of a melodeon or reed-instrument, and they are used in order to be able to place the valve and wind-chests as near the floor as possible, for the purpose of gaining sufficient space above them for the reception of the pipes or speaking-tubes within the casing of the instrument.

D represents the wind-chest, which is made in two sections or divisions, e^3 and e^4 , placed one above the other. A third and fourth division may be added upon the same principle.

Upon this principle of construction, distinct air-passages are made in each division, which conduct a large volume of air to each pipe in each set or row of pipes, and thereby compactness and portability are secured in combination with an instrument of great power and richness of tone.

These air-passages in the first division are shown at e^3 , Fig. VIII, and in the second division at e^4 , Fig. X, and are formed in single strips of boards by scroll-sawing.

Four or more of these may be sawed at the same time.

The several parts composing the wind-chest are shown, detached, in plan and section, in Figs. VII, VIII, IX, X, and XI, and these several parts are shown, combined or put together in the compact form of the wind-chest, in Fig. V.

In Fig. V the wind-chest is shown in connection with the valve-chamber, the front part of the wind-chest resting upon the back part of the valve-chamber.

These air-channels are capacious, and will conduct a sufficient quantity of air to fill the pipes, and enable them to "speak" in a rich, round, full tone of great power.

E represents the pipes, which are of common construction, but they are differently arranged within the casing of the instrument, in order to insure compactness and save room.

The pipes are considerably larger in diameter than the openings in the valve-chamber, and hence it is impracticable to place them vertically upon the openings in the wind-chest, and the length of the wooden tubes (for the base-notes) if placed vertically would require such enlargement of the casing of the instrument in height as to destroy its portability.

We obviate this difficulty by placing the longest tubes (for the base-notes) in a horizontal position, laying one tube above the other, behind the vertical pipes, and close to the back of the casing; the shortest being at the bottom and the longest at the top, so that there may be room enough for bending the end of the longest tube or tubes, as shown by red dotted lines in Fig. III.

A connection of the horizontal tubes with the wind-chest is made by means of a vertical extension or conductor, F, erected upon the wind-chest at one end of the instrument.

The openings, into which the vertical pipes are inserted, are arranged in two rows, the distance between the openings gradually increasing from one end of the rows to the other, corresponding to the gradual increase in the diameters of the pipes, as seen in Fig. XI.

The valve-openings, composing the front row, extend upward through the first division of the wind-chest, as shown in Fig. II, and connect each separately with one of the openings of the front row of tubes by passages e^1 formed in the second division of the wind-chest.

The valve-openings composing the back row connect, by passages e^2 , formed in the first division of the wind-chest, with the openings of the back row of tubes, which extend upwardly through the upper section, as is also clearly shown in Fig. II.

To supply the extension F, a row of openings, g, is made at one end of the wind-chest, and the extension F is connected to the wind-chest directly above these openings.

The valve-openings for the base-notes connect with these openings g by passages through both the first and second divisions of the wind-chest alternately; that is, one opening g being connected with its valve by a passage through the upper section, the next by a passage through the lower section, the next again through the upper section, and so on alternately to the end of the row of openings g.

In Fig. III, a plan of all air-passages through both divisions of the wind-chest is shown in dotted lines, the passages, e^2 , through the second division, being represented by black, and those through the first division, e^1 , being represented by red dotted lines.

The openings g extend through the bottom of the extension wind-chest F, and communicate with passages leading to a vertical row of openings near the back end of the extension F, into which the horizontal wooden tubes for the base-notes are fitted.

A plan of the passages through this extension is represented in Fig. II by dotted lines.

The vertical pipes in organs have heretofore been held in place by their own weight alone, their vertical position being maintained by passing them through holes made in a horizontal bridge or floor, H, which floor is made in sections, according to the different height of the tubes.

In order to make the instrument portable, the pipes need to be connected more firmly to the framework.

This we accomplish by means of a piece of wire, I, soldered on to the outside of each pipe, one end of which wire is bent at right angles to the pipe. A long bar, l^1 , is fastened to the bridge H, on one side of each row of pipes, and a slot made therein opposite each separate pipe. After the pipe has been put in its place, one quarter revolution upon its axis will pass the wire I into the slots, and fasten the pipe sufficiently to keep it in place while the instrument is being transported or moved.

In Fig. IV, two pipes are shown on a larger scale, one being fastened by this device, and the other in a position to be lifted out of the instrument.

J' represents an improved "swell," attached to the front of the casing above the key-board.

J is a stationary frame, made of thin strips of wood, placed horizontally at intervals upon vertical supporting-pieces, so that long openings are left between the said strips.

J' is a frame, of similar construction, moving in guide-grooves made in the casing of the instrument or the side-pieces of the frame J. It is so constructed that the strips of wood composing the frame J' cover the openings in frame J, in which position the frames are retained by two coil-springs, k^1 , fastened near one end of the same, the upper ends of which are connected to frame J, and the lower ends to frame J'.

In order to produce a "swell" or "crescendo," it is necessary to move the frame J' downward until its openings arrive opposite the openings of frame J, and this is done in the following manner:

l^1 are two connecting-bars, hinged to the frame J' and the rocking-arms m projecting from a shaft, n , which has bearings in the casing of the instrument. Another rocking-arm, m' , is attached to the shaft n , near one end.

O represents a counter-shaft, carrying two arms, o^1 and o^2 , the arm o^1 being located beneath and connected to the arm m' , and the other arm, o^2 , extending to the front of the instrument, where, by means of the rod p , a connection is formed with the hinged pedal p' . By pressing down the pedal, the counter-shaft o and shaft

n are made to rock slightly, the arms *m* will pull the frame *J'* downward until its openings are opposite the openings of frame *J*, and a gradual swell is produced. When the pedal *p'* is released, the springs *k k'* force the frame *J'* upward into its former position, and thereby decrease the swell.

R R are the main bellows, and *r¹ r²* the feeders.

Q is the wind-pipe, conducting the air from the bellows into the valve-chamber *C*.

S S' are the pedals, operating the feeders *r¹ r²* by means of the levers *t t'* hinged at their centres, one of their ends being connected to the foot-pedals *S S'*, and the other end to the feeders *r¹ r²* by webbing *u u'*.

This is an improvement on the manner of operating the feeders now in use; the feeding-bellows of organs being operated by only one pedal, and those of melodeons or other reed-instruments by means of connecting-rods, which make undue noise, destroying the harmony of the music when operated.

The operation of our improved pipe-organ is simply as follows:

When a key, *B*, is struck by the performer, the sticker *b²*, below it, will communicate the movement of the key to the valve *c'*, and open the same.

Air being forced into the valve-chamber *C*, by means of the bellows, it will pass through the opening communicating with the wind-chest.

If such opening is in the first row, the air will enter a passage, made in the second division, *e¹*, of the wind-chest, and be forced through an opening in the top or cover of the wind-chest, into the tube or pipe, and, by touching the "language," situated at the mouth thereof, the air produces the required sound.

If the valve-opening is in the back row, the air will be forced through a passage in the first division of the wind-chest, and enter one of the tubes or pipes composing the back row.

If the valve-opening belongs to the lower or base-notes, the air will pass through a passage in either the upper or lower section of the wind-chest, enter one of the openings *g*, and be forced into one of the horizontal wooden tubes, hereinbefore described, thus producing the required base-note.

Pipe-organs, constructed as herein described, may be made considerably smaller in size than those now in use.

They are portable, and may be shipped like pianos or melodeons, without being taken apart, and are in a fit condition for use when they arrive at their destination, without retuning, and without the aid of a skilled workman to set them up.

They require less repairing, and keep in perfect tune a longer time than any other instrument of a similar character.

They combine the quality of tone of a church-organ with the portability and convenience of a parlor-instrument, and are therefore superior to any melodeon or other reed-instrument of equal size.

By this construction we can introduce any or all of the four qualities of tone produced in a church-organ, in one instrument, and make it portable.

Taking into consideration that one set or stop of pipes exceeds in volume of tone four sets of reeds, we are enabled to produce, in a parlor-instrument, a grandeur of tone that cannot be obtained from reeds, or from any parlor-instrument heretofore constructed.

What we claim as our invention, and desire to secure by Letters Patent, is—

A compound wind-chest *D*, having two or more divisions, *e¹ e²*, each division having distinct air-passages to supply a distinct set, row, or rows, of pipes, for the purpose and substantially as described.
